UNITED STATES PATENT OFFICE.

JOHN H. W. KNOOP, OF HIGHLAND PARK, PENNSYLVANIA.

METAL FEEDER FOR LINOTYPE MACHINES.

Application filed May 17, 1923. Serial No. 639,566.

One object of my invention is to provide mechanism for feeding pig lead to the pot of a linotype, or similar, machine, when the level of the molten metal in the pot is lowered.

A further object of the invention is to feed the metal pig and to hold the metal firmly in position after the mechanism has fed it a certain distance.

10 The invention also relates to certain details, which will be fully described herein-after, reference being had to the accompanying drawings, in which:

15 Fig. 1 is a side view, partly in section, of the metal pot of a linotype machine, showing my improved mechanism for feeding pig metal into the pot;

20 Fig. 2 is a detached side view of the feeding mechanism;

25 Fig. 3 is a vertical sectional view on the line 3—3, Fig. 4, showing the pig engaged by the pivoted dog;

Fig. 4 is an end view;

Fig. 5 is a plan view;

30 Figs. 6 and 7 are detached perspective views illustrating the device;

Fig. 8 is a view similar to Fig. 3 showing the pivoted dog out of engagement with the pig and the sliding dog in engagement with said pig; and

35 Fig. 9 is another view showing the sliding dog moving down with the pig.

Referring to the drawings, 1 is a metal pot of a linotype machine having an outlet opening 2. This pot is reciprocated in the direction of the double arrow, Fig. 1, by the mechanism of the machine. 3 is the cover of the pot, in which is an opening 4. 5 is the base of my improved metal feeder having a trough-shaped guide 6 for the metal pig shown at *a*, Fig. 1. The position of the trough-shaped guide 6 is indicated properly in Fig. 1. It is slightly inclined as shown in said figure so that the pig will slide when released by the mechanism.

40 Mounted on a rock shaft 7 is a dog 8, which is arranged to engage the pig *a* and hold it in position after each feeding operation. This rock shaft is adapted to bearings 50 in the lower portion of the base 5 of the feeder. Secured to the rock shaft is an arm 9 having a forked end 10. Pivoted at 11 to a bracket 12 on the guide is a lever 13 having a double forked arm 14 that is arranged 55 to mesh with the forked end 10 of the arm 9. This lever has an arm 15 notched at 16

to be engaged by an arm 17 pivoted at 18 to a fixed point. The lever 13 has a third arm 19 to which the spring 20 is attached. This spring is also attached to a bracket 21 60 on the guide. The tendency of this lever is to move the arm to the position shown in Fig. 2 after it has been moved by engaging the end of the arm 17. This end of the arm 17 is beveled, as shown clearly in 65 Fig. 2.

22 designates a standard secured to the base 5. Pivoted to the standard, at 23, is a two-armed lever 24. One arm 25 of this lever is slotted at 26. Mounted on the lever 70 is a sliding dog 27 having a lower tooth 28 and an upper tooth 29. These teeth are arranged to engage the pig and to allow it to feed downward under control. The sliding dog has a projection 30 that passes through the slot 26 and it has a pin 31 holding it in position. The arm 32 of the lever extends under an arm 33 pivoted at 34 to the arm 24. On this arm 33 is a stop 35, which limits the movement of the lever 24. The spring 36 is located between the arm 32 and the arm 33 and tends to move the arms apart.

On the arm 33 is a curved extension 37, which is arranged to be engaged by one arm 38 of a lever 39, which is pivoted at 40 85 to the standard 22. The arm 41 of the lever 39 extends through a slot 42 in a plate 43 secured to the arm 17, Fig. 5. The arm 38 is shaped so as to rest upon the end 44 of the arm 33 when the pot is moved towards 90 the left, as shown by dotted lines in Fig. 2, and in Figs. 8 and 9; due to the fact that the arm 17 is mounted on a fixed pivot. As the mechanism is moved towards the left, the lever 39 is turned on its pivot to the 95 point indicated by dotted lines.

45 designates a spring. One end of this spring extends into a hole 46 in the arm 33. Attached to the other end of the spring is a link 47, which engages a cross bar 48 on 100 the sliding dog 27. 49 designates a float attached to a rod 50, passing through the base 5 and through a bearing 51 on the bracket 12 of the guide 6. On the upper end of the rod 50 is a head 52, which rests 105 under the arm 17, as clearly shown in Fig. 1, so that, when the metal in the pot 1 is at the proper level, the head 52 holds the arm 17 clear of the end of the arm 15 of the lever 13.

110 The mechanism, when the arm 17 is in this position, will not feed the metal. When

the metal in the pot is lowered, the float is also lowered, and the head 52 allows the arm 17 to drop into the path of the arm 15 of the lever 13 so that, when the pot moves to the left, the arm 15 comes in contact with the end of the arm 17, causing the lever to actuate the arm 9 to which is connected the dog 8, moving the dog away from the pig, which allows the pig to be lowered. As the tooth 28 of the sliding dog is in contact with the pig, the sliding dog travels downward with the pig, and, as the slot is at an angle in respect to the pig, the tooth is forced into the pig, and at the same time, the lever 24 is turned on its pivot, compressing the spring 36 until the arm 32 of the lever comes in contact with the arm 33. This movement causes the tooth 29 to engage the pig and the tooth 28 to recede from the pig.

The movement of the sliding dog downwards places tension on the spring 45 and tends to raise the lever 33. The lifting movement is stopped by the portion 44 of the lever coming in contact with the arm 38 of the lever 39. When the pot is moved to the right, the lever 39 is moved clearing the portion 44 of the arm 33 and coming in contact with the hooked extension 37, moving the mechanism carrying the sliding dog clear of the pig and allowing the spring 36 to retract the dog to its normal position. In the meantime, the spring 20 has moved the lever 13 in the direction of the arrow, Fig. 2, and has forced the dog 8 into engagement with the pig so that the dog will hold the pig in proper position until the level of the molten metal in the pot recedes, after which the above operation is repeated.

When the metal pig is first introduced into the machine, it rests on the dog 8. When the pot 1 is in motion, the pig is fed intermittently into the pot being engaged by the teeth of the sliding dog and then by the dog 8 until it enters the molten metal in the pot. When the metal has reached a predetermined height, the feeding mechanism is discontinued and the pig is held positively by the dog 8.

While my invention is especially designed for feeding pig metal to a metal pot of a linotype machine, it will be understood that it can be used for feeding metal to other machines used for like purposes, where the pot is moved towards and from a mold in making type and type slugs.

I claim:

1. In a metal feeder for linotype and like machines having a movable pot and a guide for the metal pig and a dog for holding the metal in the guide, the combination of a feeding dog for controlling the movement of the pig; and means for allowing the feeding dog to move with the pig, the feeding mechanism being controlled by a float when

the metal in the pot is below the normal level.

2. In a metal feeder for linotype and like machines having a movable pot for molten metal, and a guide for pig metal located above the pot and provided with a pivoted dog for holding the pig in position in which it is adjusted, and also provided with means for releasing the dog when the metal in the pot is below the normal level, of a feeding dog arranged to move with the pig as the pig is fed into the pot; and mechanism for controlling the dog for feeding the metal a given distance while the pivoted dog is out of engagement with the pig, with a float which controls both mechanisms.

3. In a metal feeder for linotype and like machines having a pot for molten metal and a guide for the metal pig and provided with a pivoted dog arranged to hold the pig in the position in which it is adjusted, and also provided with means for guiding the dog, with a sliding feeding dog arranged to travel with the pig as it is moved towards the pot, said feeding dog having teeth arranged to engage the pig during the feeding operation, said parts being in combination with a float which controls the mechanism which causes the pivoted dog to release the pig and to allow the sliding dog to feed the pig into the pot, the pivoted dog holding the pig in the position in which it is adjusted.

4. The combination of a movable melting pot; a base plate secured thereon; a guide for pig metal mounted on the base plate; a rock shaft mounted in the base; a dog mounted on the rock shaft and arranged to engage the pig metal; an arm on the rock shaft; a lever pivoted to a bracket on the guide and engaging the arm, one arm of the lever being in the path of an actuating arm pivoted at a fixed point; a float for raising and lowering the actuating arm; a pivoted lever; a sliding dog thereon having two teeth arranged to engage the pig; a spring for retracting the dog; a standard; a lever pivoted to the standard and arranged to be moved into the path of an arm pivoted to the first mentioned lever so as to limit the movement of the lever that carries the sliding dog so that first the lower tooth will engage the pig and then the upper tooth of the said dog, said pivoted lever, which is mounted on the standard, being controlled by the actuating arm in order to cause the sliding dog to be released from the pig after the pivoted dog has engaged the pig; and means for returning the sliding dog to its normal position.

5. The combination of a movable metal pot; a base plate mounted on the pot; a guide projecting from the base plate in which the metal pig slides; a rock shaft mounted in the base plate; a dog mounted on the rock shaft and arranged to engage and hold the pig in the position in which it is adjusted; an arm on the rock shaft having

a forked end, said guide having a bracket; a three-armed lever pivoted to the bracket, one arm of said lever having a double fork engaging the forked arm; a spring attached 5 to the second arm; a pivoted actuating arm, the third arm of the lever extending into the path of the actuating arm when the said actuating arm is lowered; a float controlling the position of the actuating arm; a stand- 10 ard on the base; a lever pivoted to the standard and having a slideway; a sliding feeding dog mounted on the slideway of the said lever, said dog having two teeth arranged to engage the pig and to allow it to feed downward; an arm pivotally mounted on the lever; a spring between said arm and an arm of the lever; a spring for retracting the sliding feeding dog; and a lever pivoted to the upper end of the standard and arranged 15 to be moved by the actuating arm into the path of the pivoted arm, or to move the pivoted arm and the pivoted lever, carrying the sliding dog, away from the pig, the sliding feeding dog engaging the pig when the pivoted dog is clear thereof.
